(57) **CLAIM**

We claim the ornamental design for a multipurpose shears, as shown and described.

DESCRIPTION

FIG. 1 is an isometric front view of multipurpose shears showing our new design;

FIG. 2 is an isometric back view thereof;

FIG. 3 is a front view thereof;

FIG. 4 is a back view thereof;

FIG. 5 is a top view thereof;

FIG. 6 is a bottom view thereof;

FIG. 7 is a left side view thereof;

FIG. 8 is a right side view thereof;

FIG. 9 is an isometric front view of a multipurpose shears in its folded up position showing our new design;

FIG. 10 is an isometric back view thereof;

FIG. 11 is a top view thereof;

FIG. 12 is a front view thereof;

FIG. 13 is a back view thereof;

FIG. 14 is a bottom view thereof;

FIG. 15 is a left view thereof; and,

FIG. 16 is a right view thereof.

The broken lines in the figures show portions of the multipurpose shears that form no part of the claimed design.
